[22] Filed: Oct. 5, 1978

[52] U.S. Cl. 406/30

[57] ABSTRACT

An automatic feed control system for a forage blower of the type adapted to be fed by a forage unloading wagon including a pressure switch connected to the blower discharge pipe, a device for controlling the discharge rate of the wagon to the blower, and electrical circuitry connecting the switch and control device so that when pressure in the discharge pipe exceeds a given level, the pressure switch actuates the control device to reduce the feed rate of the crops to the blower from the wagon.
